UNITED STATES PATENT OFFICE.

SPENCER C. CARY, OF BROOKLYN, NEW YORK, ASSIGNOR TO CARY MANUFACTURING COMPANY, OF BROOKLYN, NEW YORK, A CORPORATION OF NEW YORK.

IMPLEMENT FOR JOINING PACKAGE BINDERS.

1,411,709.

Specification of Letters Patent.

Patented Apr. 4, 1922.

Application filed January 6, 1919. Serial No. 269,752.

To all whom it may concern:

Be it known that I, SPENCER C. CARY, a citizen of the United States, residing at the city of New York, borough of Brooklyn, county of Kings, and State of New York, have invented a certain new and useful Implement for Joining Package Binders, of which the following is a specification.

The invention is a press for joining the lapping end portions of a package binder, composed of metal strapping or wire.

In prior applications Serial Nos. 246,991 and 267,937, filed by me on July 27, 1918, and Dec. 23, 1918, respectively, there are disclosed novel forms of devices for securing and sealing binders, whether of wire or strap iron, used for binding shipping boxes and packages. Generally stated, said devices embody a splice member with one or more loops or bridge members adapted by compression to be locked with the end portions of the binder, but prior to such compression the splice member is in an open condition for facilitating its application to, and adjustment to a desired position upon, the meeting portions of a binder.

The implement of this invention is especially designed for closing the splice member and for effecting a locking engagement between the splice member and the respective end portions of the binder.

It is to be noted that the binder and the locking means therefor require to be applied and secured while remaining in close contact with the shipping package, in order that there may be no appreciable slack between the package and any part of the binder, and, further, that the splice member shall be locked to the binder so as to lie substantially in the plane of said binder, thus securing a desirable compact or flat relation of the splice member to the surface of the package, as a result of which the packages can be stacked or piled firmly or solidly one upon the other without tilting said packages.

Owing to the close relation between the binder and the package due to the fact that the binder is stretched or applied under tension by an appropriate tool, and to the requirement that the metal of the binder and

the splice member shall be upset in effecting the interlocking engagement between the parts, the tool or implement of this invention is constructed with special reference for use upon binders which are under tension around the package and, also, to afford a powerful leverage in a relatively small and compact implement whereby the desired locking engagement of the splice member to the binder may be secured, and without resorting to other tools or fasteners or utilizing skilled labor.

A salient feature of the invention consists in the formation of the cooperating jaws with complementary recesses and ledges adapted in the relative movement of said jaws for retaining the splice member and the binder in the desired relation so as to preclude displacement of the splice member during the operation of compressing its loop or loops and of upsetting the binder for the accomplishment of the primary function in effecting the interlocking engagement between the splice member and the binder.

In a preferred form, the implement is constructed with a lower jaw which is relatively thin to facilitate the operation of fitting it below the binder and splice member, said lower jaw having on its working face a plurality of ledges separated by an intervening channel the bottom of which is in the plane of the upper face of said jaw. The lower jaw is formed with a handle and with upstanding flanges, which flanges afford the means whereby the pivots are supported for an upper jaw and for a lever. Said upper jaw is formed on its under face with a ledge positioned in a plane above the under face and producing a groove between two other channels, the depth of which other channels exceed the depth of the groove. The jaws are so assembled that the ledge of the upper jaw is opposite to the channel in the lower jaw, whereas the ledges of the lower jaw are opposite the channels of the upper jaw. The described formation of the jaws perform the function of retaining the splice member against displacement during the relative movement of the jaws, more particularly the pivotal movement of the upper

jaw toward the lower jaw, and the further functions of compressing the loops of the splice member and of upsetting the binder so as to compress the splice member into the plane of the binder and to effect the desired interlocking engagement between said splice member and the binder.

Other features and advantages of the invention will appear from the following description taken in connection with the drawings, wherein—

Fig. 1 is a vertical central section partly in elevation of the improved implement showing the jaws opened.

Fig. 2 is a similar section with the jaws closed, the plane of the section being indicated by the dotted line 2—2 of Fig. 3.

Fig. 2^a is a perspective of a part of the lower jaw.

Fig. 3 is a cross section on the line 3—3 of Fig. 2.

Fig. 4 is an under plan view of the movable jaw.

Fig. 4^a is a perspective of part of the upper jaw.

Figs. 5 and 6 are top and bottom plan views of the splice member and the binder after said parts are interlocked.

The lower jaw A is constructed in a way to secure the required strength and to be relatively thin in cross section, the forward end portion *a* being tapering to facilitate its entry between the box and the strap. This jaw is provided with a suitable handle bar A' preferably integral with the jaw, and at the side portions said jaw is provided with longitudinal flanges *b* which are fashioned to produce lugs *b'*.

B is the upper jaw composed of a relatively flat metal plate, the same being positioned between flanges *b* and lugs *b'* and one end portion of said jaw being hung on a pin *c*, the latter passing through flanges *b* whereby the upper jaw is pivotally mounted at the rear portion thereof.

A spring C is positioned intermediate the jaws and acts to lift the upper jaw away from the lower jaw for the purpose of introducing the binder and the splice member between the jaws. As shown, the spring is retained in sockets *c'* provided in the opposing faces of the jaws.

The jaws are closed together by the movement of a lever D, the latter being of any appropriate length and constructed so that it will have the movement and power required for effectively upsetting the metal so as to interlock the splice member and the binder. A part only of this lever is shown, but the lever bar is enlarged to produce a head *d*, one edge portion of which is eccentric to the axis of movement of the lever, thus resulting in a cam *e*. The lever head lies between the lugs *b'*, and said lever is

fulcrumed by a pin *f* which passes through 65 the lugs and the lever head, whereby the lever is pivotally connected with the lower jaw and it is positioned for the cam *e* to ride upon the upper jaw when moving the lever toward the left in Figs. 1 and 2. 70 Suitable means are or may be provided for arresting the movement of the lever; as shown, the head *d* is formed with a stop surface *g* adapted to bite upon the jaw B when the operation of upsetting the binder 75 and the splice member is effected. It is apparent that other means for arresting the lever may be provided by a skilled mechanic, but it is desirable to provide some stopping means for the reason that the operator must 80 pull the lever over far enough to bring the stopping means into action in order to effectively lock the splice to the binder.

The opposing faces of the jaws, termed the working faces, are desirably fashioned 85 for upsetting the metal. As shown, the flanges *b* of the lower jaw terminate backwardly of the forward end *a* of said jaw, and on the upper face, said lower jaw is formed with a plurality of ledges *h* which 90 are separated by an intervening channel *h'*, see Figs. 2^a and 3. The upper jaw is formed on its under face with a plurality of channels *i* and with a ledge *k*, the latter being intermediate the channels, see Figs. 3 and 95 4^a. The height of ledge *k* is less than the depth of channels *i* so that a recess *l* is formed between the under face of the ledge *k* and the under surface of the jaw, as clearly shown in Fig. 4^a.

The channel *h'* between the ledges *h* of the lower jaw receives the splice member P in such manner that movement of said splice member relatively to the jaw is precluded by said ledges, thus effectively retaining the splice member in position prior to closing the jaws upon the splice member and the lapping portions of the binder. As noted, the height of the ledge *k* on the upper jaws is less than the depth of the channels *i*, 110 so as to make provision for the accommodation of the three thicknesses of metal comprised in the two end portions O O of the binder and the loop *p* of splice member P, and when pressure is applied by the co-operating jaws, the ledge *k* of the upper jaw and the ledges *h* of the lower jaw mutually 115 co-operate to displace the metal of parts O, O, P, in such manner that the loop *p* of part P is compressed between *k* *h'*, where- 120 as certain portions of O, O, are offset between parts *h*, *i*, *h*, *i*, of said jaws for the performance of the function of upsetting the metal parts O, O, P, and to thereby interlock the binder and the splice members.

The two jaws are relatively positioned for the working faces to oppose each other; thus, the ledges *h* of the lower jaw are opposite

to the channels *i* of the upper jaw, whereas the ledge *k* of the upper jaw is opposite the channel *h'* of the lower jaw.

The material to be operated upon is shown 5 as a flat metal strap *O* and a splice member *P*, said splice member having a single loop or bridge member *p*, although a plurality of such loops or bridge members may be used as disclosed in my prior applications.

10 In operation, the end portions of the binder *O* are engaged by the splice member *P* after the binder shall have been placed under tension, said loop *p* of the splice member being open as shown in Fig. 1 so that 15 the splice member may be slipped easily upon the binder and adjusted thereon to the required position relatively to the twolapping end portions of said binder. With the lever *D* swung forwardly and the jaws *A* *B* 20 opened, see Fig. 1, the nose *a* of the lower jaw is thrust below the binder and the splice member until said splice is between the working faces of the two jaws. The lever is now turned toward the rear until arrested by 25 the stop face *g*, see Fig. 2, the effect of which lever movement is to bring the cam *e* into action and to forcibly press the upper jaw toward the lower jaw. During the closing movement of the jaws, the ledge *k* of the 30 upper jaw acts upon the loop *p* of the splice member to compress the latter, and the ledges *h* *h* of the lower jaw act upon the binder to upset the latter, and to bring the splice member into the plane of the binder, 35 the upset or displaced portions of the splice member and of the binder being received into the channels *h'* *i*, *l*, of the jaws. The splice member and the binder are thus displaced to effect a mutual interlocking of said 40 binder and splice member, and during this operation the ledges on the working faces of the jaws act to retain the splice member in position, more particularly during the swinging movement of the upper jaw toward 45 the lower jaw, the operations of pinching the metal parts *O* *P* having no tendency in this implement to shove the metal out of the way.

From the foregoing it will be understood 50 that the implement embodies means for securing a relatively powerful leverage in order to upset the metal of the parts *O*, *P*, and effectively lock the same together for holding the binder under tension.

55 After the implement is operated to close the jaws and thereby interlock the splice member and the binder, the lever is swung over toward the right and the spring opens over the jaws, thus permitting the implement to 60 be removed easily and quickly from the locked binder.

Having thus fully described the invention what I claim as new and desire to secure by Letters Patent is:—

65 1. An implement for joining the end por-

tions of a package binder by a splice-member embodying a lower jaw provided in its upper face with a plurality of parallel ledges and with a channel intervening said ledges, said ledges and the channel being relatively 70 positioned for receiving and retaining the splice-member, an upper jaw provided on its under face with a plurality of channels and with a ledge intervening said channels, the height of said ledge being less than the 75 depth of the channels, the ledges and the channel of the lower jaw being in registering relation to the channels and the ledge of the upper jaw, and means for imparting relative movement to said jaws. 80

2. An implement for joining the end portions of a package binder by a splice-member embodying a lower jaw provided with a tapering forward portion of thin cross section and with a rigid handle, said jaw being provided on its upper face with a plurality of ledges and with a channel intervening said ledges, said ledges and channel of said jaw being relatively positioned for receiving and retaining the splice-member against movement with reference to the jaw, an upper jaw provided on its lower face with a plurality of channels and with a ledge intervening said channels, the height of said ledge being less than the depth of the channels, 90 and the channels and ledge of the upper jaw being in registering relation to the ledges and channel of said lower jaw, and a cam lever fulcrumed on the lower jaw for the cam thereof to press the upper jaw relatively to the lower jaw. 95

3. In an implement for joining the end portions of a package binder by a splice-member embodying a plurality of co-operating jaws the side portions of which are open 105 and free for the passage of said binder, one of said jaws being provided on its upper face with upstanding ledges separated by an intervening channel lying in the plane of said upper face and the other of said jaws 110 having on its under face a depending ledge positioned intermediate a plurality of channels, the depth of which exceeds the height of the depending ledge, the ledges and channel of the first jaw being in registering relation to the ledge and spaces of the second jaw and said first jaw operating to retain against displacement the splice member at and during the closing movement of said jaws. 115

4. In an implement for joining the end portions of a package binder by a splice-member, comprising a plurality of co-operating jaws the side portions of which are open and free for the passage between the 120 jaws of said binder, the lower of said jaws being provided with ledges upstanding from the face of the jaw and positioned at the respective sides thereof, said ledges being separated by a channel lying in the plane of the 125 130

face of the jaw, and the upper of said jaws being provided on its under face with a ledge and with channels the depth of which exceeds the height of the ledge, said ledges and channel of the lower jaw affording means for retaining a splice-member against displacement at and prior to the closing movement of the jaws and the ledges and

channel of the lower jaw being in registering relation to the channels and ledge of 10 the upper jaw.

In testimony whereof I have hereunto subscribed my name this 4th day of January, 1919.

SPENCER C. CARY.
